UNITED STATES PATENT OFFICE

CHARLES G. BANKS, OF LOS ANGELES, CALIFORNIA

JOINT FOR ALL METAL ROTARY HOSE FOR OIL WELLS

Application filed November 27, 1929. Serial No. 410,105.

This invention relates to rotary hose of the type use in connection with hydraulic rotary drilling equipment for drilling oil wells and the like, and deals particularly with joints 5 incorporated in an all metal hose for this purpose.

Reference is made to my co-pending application, Serial No. 366,202, filed May 27, 1929, entitled all metal high pressure hose for 10 oil wells, wherein I have illustrated and described an articulated all metal hose of the character involved in this invention.

In drilling oil wells with hydraulic rotary drilling equipment, it is common practice to 15 conduct the circulating fluid from a standpipe supported by the derrick to a swivel head mounted upon a kelly which in turn drives a drill string extending in the well bore. The means of conducting the circulating 20 fluid from the standpipe to the rotary swivel head has been termed by common usage, the rotary hose. This invention purports to deal with this particular unit.

A great many difficulties have arisen in 25 the use of the present available types of rotary hose. The generally used fabric hose has been found to deteriorate rapidly due to oil which has been taken up by the circulating fluid and also due to excessive strain 30 applied to the hose at points of bending. Furthermore, no efficient means has been developed for satisfactorily connecting the ends 35 of a fabric hose to the gooseneck on a standpipe and the gooseneck on the swivel head. In addition to this, fabric hose has been 40 found inadequate to withstand the excessively high pressures that oftentimes occur due to the phenomenon of a water hammer in the drill string. Many types of expensive hose 45 have been produced in an attempt to provide a hose that fully meets the requirements of the oil well drilling practice. However, in so far as I am aware there is no hose, except 50 those disclosed in my co-pending applications, which will withstand the same amount of pressure as the drill string.

An all metal hose of the character described in my co-pending application may, by proper designing, be made sufficiently strong to withstand higher hydrostatic pressure than the

drill string. This would be an ideal arrangement.

In producing an articulated all metal rotary hose of the type contemplated by this invention, it becomes imperative that joints 55 be provided which permit free relative movement of sections of the hose under the high pressures encountered in drilling operations. Accordingly, it becomes a prime object of this invention to provide joints characterized 60 by having comparatively free movement between the moving parts.

In dealing with the high pressures encountered in drilling deep wells with a hydraulic rotary drilling outfit, considerable 65 attention must be given to relieving the movable joints in a hose of the character contemplated by this invention of as much internal pressure as possible. My invention 70 recognizes this fact and, therefore, provides means for transferring a part of the hydraulic pressure from bearing upon the movable parts of such joints to the casings of the joints. In order to accomplish this, I conceived the idea of supporting the cup leather 75 upon the casing instead of upon the movable part within the casing. In this manner, I have effectively removed all the hydraulic pressure bearing upon the cup leather from the rotatable part to the fixed part of the 80 joint. This arrangement will be appreciated as materially decreasing the pressure upon the movable part and will be recognized as a means to the end of this invention. By 85 mounting a cup leather in this manner, I not only reduce the hydraulic pressure upon the movable parts, but I also reduce the area of contact of the cup leather with the movable part, and as a result reduce the power necessary 90 to turn the joint under high pressure. An added advantage is derived from the simplicity of the structure wherein a minimum number of parts are employed, such parts being readily accessible and replaceable in 95 case of wear.

Another feature of my invention resides in the fact that I have provided a unit construction that may be combined in several 100 combinations to produce various joints meet-

ing the stringent requirements in a hose of the character described.

It is also obvious that the prime feature of my invention may be incorporated with other types of joints and as an illustration, I have shown the feature of this invention as embodied in connection with a ball joint which yields a very definite benefit when used in an all metal rotary hose.

10 A further feature of my invention resides in the manner in which I minimize the internal wear of parts caused by the sharp turning of the circulating fluid. For this purpose, I have provided an especially formed head wherein the fluid in turning is caused to form a cushion against the walls of the head and thereby decrease any wearing action of the fluid.

20 In assembling joints of the character contemplated by this invention, it is necessary in order to obtain proper movement that the axes of said joints be arranged in a prescribed manner. This arrangement, when used with taper threads has been found at 25 times to necessitate excessive tightening of conduit connections in order to orient joints to the proper planes of rotation. It, therefore, becomes an object of this invention to provide means whereby conduit connections may 30 be rotated to bring the joints into their proper position without placing undue strain upon the conduit connection.

35 Other objects and advantages will appear in the description when read in connection with the drawings in which

40 Fig. 1 fragmentarily illustrates the manner in which a rotary hose of the type contemplated by this invention is employed in connection with hydraulic rotary drilling equipment;

Fig. 2 is a side elevation of one of the joints used in a hose of this type and may be termed a universal joint;

45 Fig. 3 is an end view on line 3-3 of Fig. 2;

Fig. 4 is another type of joint contemplated by this invention and may be considered as a simple swing joint;

50 Fig. 5 is another type of joint contemplated by this invention and used in a hose of this character and is termed a swing and swivel joint;

55 Fig. 6 is a vertical section of Fig. 5 taken in the plane of the paper;

Fig. 7 is a sectional elevation showing another form of friction bearing which may be employed in conjunction with my invention;

60 Fig. 8 is a plan view taken on line 8-8 of Fig. 5 and diagrammatically shows the way in which I obtain a water cushion to prevent excessive wear of the circulating fluid when diverted from its normal course.

65 In the drawings, I have shown my inven-

tion as embodied with the usual rotary hydraulic oil well drilling equipment.

In Fig. 1, I have fragmentarily illustrated a derrick leg designated at A and having a 70 circulating fluid standpipe B suitably supported thereby. In conjunction therewith, I have shown a rotary table 11 having a kelly 12 conventionally mounted therein and a swivel head generally designated at 13 supported upon the kelly. A block and tackle generally designated at 14 is supported in the usual manner and by means of a hook 15 supports the swivel head 13 by the bain 16. As shown, the swivel head 13 is provided with the conventional gooseneck 17 which is equipped with the usual valve 18 and a conventional union 19. The standpipe B is also provided with a gooseneck 20 and an articulated all metal hose, generally designated C of the type contemplated in this invention, extends between the union 19 and the gooseneck 20. In this hose, I have provided a series of joints each especially adapted for a certain purpose and have designated these joints as D, D', and D'', to signify the various types of joints used. The joint D may be termed a universal joint, and is particularly adapted to provide the necessary movement required in a rotary hose between the points of connecting the hose to the standpipe and the swivel head. The joints D' may be defined as swing joints, and are used in the intermediate connections of the hose sections. The joint D'' is of a slightly different character than the joint D' in that it embodies in addition to the swing joint a swivel joint and, consequently, is termed a swing and swivel joint. It is one of the purposes of this invention to provide joints corresponding to the above enumerated types, and also to provide a simplified structure for such joints wherein the utility of said joints is enhanced by reducing the internal friction within said joints when movement takes place.

In Figs. 2 and 3, I have shown illustrations of the joint D. More specifically described, this joint consists of an arrangement of two swing joints E and F mounted upon the ends of an elbow G together with a swivel ball joint H. It is evident that such an arrangement provides a universal movement between the conduits 21 and 22. Since a rotary hose requires a universal movement as before stated at the points of connection to the swivel head and the standpipe, this joint provides a satisfactory unit for such a purpose.

In Fig. 4, I have illustrated the joint D' which is shown as comprising a swing joint 125 K having an elbow G with a conduit connection 23 upon the outwardly extending end. This joint will be appreciated as providing a swing movement in one plane only between the conduits 24 and 25, and, as before stated, 130

is adapted to form connections between the intermediate sections of the pipe.

In Fig. 5, I have illustrated the joint D''. This joint will be observed to be similar to D', the only difference being that the conduit connection 23 is converted into a swivel joint H. This structure will be recognized as providing a swing and swivel joint, and has a special purpose when used in a hose of the 10 character described in that it provides rotative movement in the hose line near the lower end of the hose. In practice, at least one of these joints should be incorporated in every hose.

In Fig. 6, I have detailed the specific construction of the unit constructions involved in my invention. This figure is a vertical section taken on the center line of Fig. 5 in the plane of the paper. More specifically 20 describing the structure of this joint, it is seen to comprise the elbow G upon one end of which is mounted my preferred construction of a swing joint designated at K and upon the other end of which is mounted a 25 type of ball socket swivel joint generally designated H. It is to be understood that the joints K and H exemplify the joints contemplated by this invention. The means of 30 mounting the swing joint K upon the end of the elbow G consists of a casing 26 into which an open end 27 of the elbow G extends. For purposes of further identification, the casing 26 and the parts rigidly associated therewith may be termed the fixed element or housing 35 and the elbow G the movable element. That portion of the elbow G which extends into the casing 26 I may term the inner conduit section. In this form of my invention, the 40 internal conduit section is provided with a short run of screw threads 28 onto which is screw-threadedly mounted a collar 29 which is adapted to bear upon ball-bearings 30 that are in turn supported upon an inner 45 extending flange 31 which is a part of the casing 26. Attention is directed to the fact that the ball-bearings 30 bear directly upon the flange 31 and support the elbow G by bearing directly against the collar 29. This 50 structure appreciably reduces the offset distance between the entering and exiting passages. This structure will be readily recognized as providing a close coupled anti-friction means of supporting the elbow G within the casing 26.

Means are provided for transferring part 55 of the hydrostatic pressure from the anti-friction bearing to the casing 26, and preferably consist of a ring 32 mounted in a recess 33 of the casing 26 and having an opening 34 adapted to receive the open end 27 of the elbow G. A cup leather 35 is mounted upon the ring 32 and as a means of holding the cup leather 35 in operative position, I have provided a closure head generally designated 37, 60 which is adapted to fit over the casing 26 and

be held thereagainst by bolts 38. The head 37 is provided with a recess 39 that is adapted to fit over the ring 32 and also has a second recess 40 that is arranged to bear upon the cup leather 35 and form a water seal therebetween. The head 37 is further equipped with a conduit connection 41 lying substantially at right angles to the axis of rotation of the joint K. From the construction just described, it will be seen that the casing 26 and the closure head 37 cooperate to form what I may term a housing in which the ring 32 (54—Fig. 7) and the flange 31 (57—Fig. 7) constitute inwardly extending 70 annular shelves adapted to support the packing ring 35 (53—Fig. 7) and the bearing flange 29 (55—Fig. 7) respectively. It is clearly evident, under this arrangement, that the pressure upon the cup leather 35 is transmitted to the casing 26 and the associated elements forming the housing and that the anti-friction bearing means are, consequently, relieved of this amount of pressure. It is also clear that by mounting the cup leather in this manner the area of leather that slidably contacts the moving surface is reduced from the diameter of the casing to the diameter of the elbow. This will be readily appreciated as materially reducing the power required to turn a joint of this character under high 80 pressure. On the opposite end of the elbow G, I have shown a somewhat different joint designated at H in which a ball and socket arrangement is utilized. In this arrangement I employ a cup leather 42 supported upon a ring 43 in the manner identical with that described in relation to the joint K. The bearing means in this instance consist of a casing 44 formed as a socket to receive a spherical shoulder 45 formed integrally with a rotating member 46. The casing 44 is attached to the flaring end 47 of the elbow G by means of bolts 48, and the ring 43 and the cup leather 42 are held therebetween in the identical manner described with relation to the joint K. The rotatable member 46 is provided with a retaining socket 49 screw-threadedly mounted by means of threads 50 upon the exterior of the member 46. A lock nut 51 is provided to hold the retaining member 49 in fixed position upon the threads 50. The extending end of the rotating member 46 is provided with screw-threads 52 to receive a tool joint of standard construction. The joint H thus provided will be appreciated as a providing a rotative movement as well as a universal movement. This feature has been found particularly useful when used in connection with the swing joint K or when used in connection with a pair of swing joints such as E and F, or it may be used to constitute a joint of itself.

In Fig. 7, I have shown another form of supporting the elbow G in a swing joint designated L. In this construction, a cup leath-

er 53 is mounted upon a ring 54 in the usual manner but in place of the ball-bearing arrangement as shown in the joint A, I have provided a sliding means preferably consisting of a collar 55 screw-threadedly mounted upon the inner end of the elbow G. The collar 55 in turn bears upon an antifriction washer 56 supported upon an inner extending flange 57 of the casing 26. In both of the forms shown in Figs. 6 and 7, I have shown means of locking the collars 26 and 55, respectively, to the elbow G which preferably consists of a pin 58 extending through said collars and into a shoulder 59 provided on the elbow G.

In practice, it often times happens that in order to properly orient a joint with respect to its axis of rotation, the use of taper threads has been found to be highly objectionable. In order to obviate such practice, I have incorporated with each of my conduit connections a copper ring 60 mounted in a recess 61 at the base of the threads 62, best shown in the conduit connection 41 in Fig. 6. In utilizing a joint of this character, the threads 62 are straight-run threads, i. e., they have no taper, and the conduit 63 is accordingly freely screwed into the conduit connection 41 until the end of the conduit 30 engages the copper gasket 60. The copper gasket is provided for the purpose of permitting additional screwing movement to take place until the joint has been oriented into its proper axis. This structure will also be appreciated as providing an effective water seal and a lock against unscrewing of the parts.

This invention also includes a means of diverting the circulating fluid in a manner to minimize internal wear of the parts. For this purpose I have formed the closure head 37 in a manner to cause the liquid to flow substantially in the direction of the arrows indicated in Figs. 6 and 8. In these figures it will be noted that the conduit passage, designated 65, expands with respect to the cross-section. There is also an extended portion 66 which forms a circular chamber 66' beyond the open end 67 of the elbow G.

As shown in Fig. 8, at 68, the side walls of the closure head also expand and extend outside the opening 67. This arrangement causes the fluid to flow around a spherical path defined by the inner wall of the head and to meet somewhere in the vicinity diametrically opposite the fluid entrance. The flows then unite and descend through the opening 67 substantially in the direction of the arrows shown in Figs. 6 and 8. It is evident, under this arrangement, that a substantially smooth flow of fluid is provided and that, as a result, there is no scouring action upon the interior of the head 37.

Although I have shown my invention as applied to a rotary hose, nevertheless I am

aware that certain features of my invention may have a usefulness outside of this application shown. I, therefore, intend this disclosure to include all such applications and modifications of my invention as fall within the scope of the specification and the essence of the invention as expressed in the appended claims.

I claim as my invention:

1. A conduit joint of the character described comprising: a casing; a closure head for said casing and a movable element mounted in said casing; a fluid sealing means between said closure head and said movable element; means for supporting said fluid sealing means upon said casing, said last mentioned means including a ring arranged to bear upon said casing and adapted to freely receive said movable element; and a cup leather supported upon said ring and arranged to movably engage said movable element.

2. A conduit joint of the character described comprising: a casing; a closure head for said casing and a movable element mounted in said casing; a fluid sealing means between said closure head and said movable element; means for supporting said fluid sealing means upon said casing, said last mentioned means including a ring mounted between said casing and said closure head and adapted to freely receive said movable element; and a cup leather supported upon said ring and arranged to movably engage said movable element.

3. A conduit joint of the character described comprising: a casing; a closure head for said casing and a movable element mounted in said casing; a fluid sealing means between said closure head and said movable element; means for supporting said fluid sealing means upon said casing, said last mentioned means including a ring arranged to bear upon said casing and adapted to freely receive said movable element; and a cup leather supported upon said ring and arranged to movably engage said movable element and adapted to be held in place by said closure head.

4. A conduit joint of the character described, a fixed element and a movable element; fluid sealing means between said fixed element and said movable element fixedly supported on said fixed element and adapted to be forced by fluid pressure into pressure engagement with said movable element; means for rotatably supporting said movable element in said fixed element, said last mentioned means including a casing having an inwardly extending flange; a collar mounted on said movable element; and antifriction means interposed between said flange and said collar.

5. A conduit joint of the character described, a fixed element and a movable ele-

ment; fluid sealing means between said fixed element and said movable element fixedly supported on said fixed element and adapted to be forced by fluid pressure into pressure engagement with said movable element; means for rotatably supporting said movable element in said fixed element, said last mentioned means including a casing having an inwardly extending flange forming a ball race; a collar mounted on said movable element forming a ball race; ball-bearings interposed between said flange and said collar.

10 6. In conduit joints of the character described, a fixed element and a movable element; fluid sealing means between said fixed element and said movable element supported on said fixed element; and means for rotatably supporting said movable element in said fixed element, said last mentioned means including a casing having a spherical seat, and said movable element having a spherical shoulder adapted to universally engage said seat.

15 7. In conduit joints of the character described, a fixed element and a movable element; fluid sealing means between said fixed element and said movable element supported on said fixed element; means for rotatably supporting said movable element in said fixed element, said last mentioned means including a casing having a spherical seat, and said movable element having a spherical shoulder adapted to universally engage said seat; and retaining means for holding said shoulder in engagement with said seat.

20 8. A conduit joint of the character described embodying: a housing; an inner conduit section received in said housing; a bearing flange on said inner conduit section; an annular shelf in said housing extending inwardly below said bearing flange; a second annular shelf in said housing above said bearing flange; and a packing ring supported in said housing by said last mentioned shelf with its throat portion engaging the outer surface of said inner conduit section.

25 In testimony whereof, I have hereunto set my hand at Los Angeles, California, this 50 18th day of November, 1929.

CHARLES G. BANKS.
